DIAGNOSTIC INSTRUMENT HEAD

Melvin C. Burrett, Whittier, Calif., assignor to
Bausch & Lomb Optical Company, Rochester,
N. Y., a corporation of New York

Application July 24, 1953, Serial No. 26,125

Term of patent 14 years

(Cl. D83—1)

To all whom it may concern:

Be it known that I, Melvin C. Burrett, a citizen of the United States and a resident of Whittier, county of Los Angeles, and State of California, have invented a new, original, and ornamental Design for a Diagnostic Instrument Head, of which the following is a specification, reference being had to the accompanying drawing, forming a part hereof.

Fig. 1 is a perspective view of the left side of a diagnostic instrument head showing my new design.

Fig. 2 is a similar view of the right side thereof.
Fig. 3 is a top plan view thereof.

Fig. 4 is an end elevational view thereof.
The essential features of my design are shown in full lines on the drawing.

I claim:

The ornamental design for a diagnostic instrument head, substantially as shown and described.

MELVIN C. BURRETT.
